CLAIM

The ornamental design for a marine vehicle camping light adapter, as shown and described.

DESCRIPTION

FIG. 1 is a right side view of the marine vehicle camping light adapter of the present invention wearing a foot with stakes for use on land.

FIG. 2 is a left side view of the marine vehicle camping light adapter of the present invention wearing a foot with stakes for use on land.

FIG. 3 is a bottom view of the marine vehicle camping light adapter of the present invention wearing a foot with stakes for use on land.

FIG. 4 is a top view of the marine vehicle camping light adapter of the present invention wearing a foot with stakes for use on land.

FIG. 5 is a front view of the marine vehicle camping light adapter of the present invention wearing a foot with stakes for use on land; and,

FIG. 6 is a back view of the marine vehicle camping light adapter of the present invention wearing a foot with stakes for use on land.

Elements depicted by dotted lines are not part of the invention. Shading has been minimized to clarify narrow elongated parts. In the case of fabric shading, a bitmap image of the shading presented in the illustrations of MPEP Chapter 608.02 is used, substantially reduced in size due to the small size of the strap shaded therewith.
